 Underwood Elliott Fisher Company, New York,
 N. Y., a corporation of Delaware

Application December 30, 1940, Serial No. 372,297

29 Claims.

(Cl. 197—63)

This invention relates to key-settable margin stop mechanisms for typewriting machines, and more particularly to mechanisms of this character having provision for typing beyond each margin.

One of the objects of the invention is to provide a key-settable margin-stop mechanism having a simple and reliably operative margin-release device adapted upon actuation of a control key to release the carriage from within the normal line-typing limits, for typing beyond either margin, and adapted to be automatically reconditioned for the normal margin gaging of a typing line by merely returning the carriage to within the line-typing range.

A further object is to provide a margin-release mechanism which is normally locked against release in all line-typing positions of the carriage, thereby to forestall unintentional margin release which would render the margin-stop mechanism temporarily ineffective for normal margin gaging.

Another object is to provide, in association with a margin-gaging mechanism having provision for automatically restorable margin release and having letter-spaced carriage stops of identical form adapted to function either as left or right margin stops, an improved stop setting mechanism rendering a set stop effective for either right or left margin gaging.

A further object is to provide a safety device associated with the key-operable stop setting mechanism to prevent damage to the mechanism which would otherwise result when the setting mechanism is forcefully operated with the carriage banked at the line-start position.

The invention in certain respects constitutes an improvement on the one described and claimed in my copending application Serial No. 341,420, filed June 20, 1940, now Patent No. 2,316,865, dated April 20, 1943, and is also an improvement on the mechanism shown in the U. S. patent to Dobson, No. 2,196,790, dated April 9, 1940.

Improvements over the present invention are described and claimed in a copending application of Newberry, filed April 21, 1942, now U. S. Patent No. 2,341,470 issued February 8, 1944.

In the physical embodiment of the invention illustrated, a series of key-settable stops identical in form are arranged at letter-space intervals on the carriage and are settable from a normal, ineffective position on the stop rack to an effective position engageable with a counterstop. A key-operated stop setter is adapted to set any one of the stops positioned thereat by carriage

movement, at a stop setting station to the left of the counterstop in its normal position. Operation of a right-hand stop-setting key causes the counterstop to be shifted to the left of the setting station so that the stop being set serves to gage the line-end position of the carriage. The stop-setting mechanism includes a safety device to prevent damage to the mechanism when forcefully operated to set a right-hand stop with a left stop banked against the counterstop, the safety device yielding to allow the setting mechanism to move idly without damage to the working parts. Margin-release mechanism is provided which, upon operation of a release key, retracts the counterstop from its normally effective position, thereby releasing the carriage for typing in either margin. A normally disabled latching device, conditioned for operation by depressing the release key, is rendered effective by relative movement of the counterstop and carriage with the latter banked at either margin. In that to effectively set the latching device requires relative movement of the carriage and counterstop, unintentional margin release which would render the stop mechanism temporarily ineffective for normal margin-gaging is prevented. Said latching device holds the counterstop retracted during in-the-margin typing and is released automatically, to free the counterstop for its normal margin-gaging function, by movement of the carriage to within-the-line-typing zone defined by the set margin stops.

In the drawings:

Figure 1 is a front elevational view of the margin-stop mechanism of the invention, in the condition of normal line typing, omitting the stop restoring element to facilitate illustration.

Figure 2 is a sectional view taken on a fore-and-aft plane of the typewriter, showing the margin-stop mechanism in side elevation.

Figure 3 is a fragmentary plan view taken on line 3—3 of Figure 2.

Figures 4 and 5 illustrate the condition of the mechanism in setting a stop for either left or right margin gaging, Figure 4 showing a stop set to define the beginning of a line, and Figure 5 showing the stop set for line-end gaging.

Figure 6 shows the condition of the mechanism with the carriage banked at the beginning-of-line position, or preparatory to release for typing in the left margin.

Figure 7 shows the mechanism in operated condition for typing in the left margin.

Figure 8 illustrates the condition of the mech-

anism with the carriage at line-end or key-locked position.

Figure 9 shows the mechanism in an intermediate condition of operation for margin release from the line-end position.

Figure 10 illustrates the margin-release operation completed for release from the line-end position, in readiness to type in the right-hand margin.

Figure 11 represents the mechanism in condition following the Figure 10 showing, after having begun typing in the right-hand margin.

Figure 12 demonstrates the action in restoring the mechanism from margin release for the usual typing between the margin-gaging stops.

Figure 13 shows the operation of the safety device in yielding to prevent damage to the mechanism when operated to set a right-hand stop with a left stop banked against the counterstop, and

Figure 14 is an exploded perspective view of the counterstop and other elements directly associated therewith, also showing the stop setter.

Referring to the drawings for a more detailed description thereof, and particularly to Figures 1 and 2, the typewriting machine forming the embodiment illustrated includes a carriage 16 having end members 17 rigidly connected by a cross member 18 presenting a carriage rail for guiding the carriage in line-typing movement in cooperation with trackways 19 supported on the main frame of the machine. The machine may include the usual typing instrumentalities having keys, not shown, for actuating type bars 20 to strike a platen 21 on the carriage. The carriage is actuated in letter-feed direction by the usual spring drum, not shown, under control of an escapement mechanism 22, the wheel 23 of which may be geared to the carriage by a pinion 24 and carriage rack 25. The carriage may be advanced step by step in the conventional manner by the type bars engaging a universal bar 26 connected to a rockable bail 27 pivoted at 28 and having an operative connection 30 to an escapement dog carrier 31 cooperating with the wheel 23 in the well-known manner. During each type bar stroke, the carriage is advanced a letter space in line-typing direction so that the type characters are successively imprinted in a typing line on the work sheet supported on the platen.

A series of margin stops 34, identical in form throughout the range of carriage travel, are arranged at letter-space intervals on the carriage and are supported by a rack bar 35 secured at each end to the carriage. Each stop 34 is slideable in the rack bar for position adjustment from a normal, ineffective setting to a projected position at which the lower end of the stop is disposed to engage a counterstop 36 during carriage travel. A detent spring is provided to yieldably hold the stop at either of said positions. The stop rack organization may be of any suitable arrangement such as that shown and described in my Patent No. 2,146,821, dated February 14, 1939.

A bracket 37, secured to the rear trackway 19, or other fixed member of the machine, supports a pivot 38 providing a pivotal mounting for the counterstop 36 and other elements hereinafter described. The pivot 38 includes a screw 40 and a collar 41 threaded thereon, mounted on the bracket 37 as shown in Figures 2 and 14. The counterstop 36 has a slotted portion 42 engaging the pivot 38, allowing the counterstop to swing laterally and move up and down, a spring 43 yieldably holding the counterstop in normal,

raised position in the path of the set carriage stops 34, Figure 1.

5 A shift lever 44 is pivoted intermediate its ends on the pivot 38 and serves both to guide the upper end of the counterstop 36 laterally and to shift same laterally to positions at either side of a stop-setting station. The upper end of the shift lever 44 has a forwardly extending lug 45 slotted to slidably receive the counterstop 36. The lower portion of the lever 44 presents a shifter cam 46 cooperative with mechanism hereinafter described. A spring 47, assisted by spring 43, urges the upper portion of the shift lever and the counterstop rightward to its normal position as defined by the engagement of the lug 45 with one side of a guide slot 48 in a cover plate 50.

10 The stop-setting mechanism is so organized that any stop 34 positioned by carriage movement at the stop-setting station may be set for either 20 right- or left-hand margin gaging. Two stop setting keys 51, 52 are arranged adjacent the type keyboard of the machine for setting respectively the left margin and right margin stops, see Figure 1. Operation of either key 51 or 52, causes 25 a stop setter 53 to be pulled downwardly so that a finger 54 thereon, in position at the stop-setting station, projects the one stop 34 of the series at said station. The key 51 for setting a stop for left-hand margin gaging, is carried on a 30 key lever 55 fulcrumed on a comb bar 56 and engageable with an intermediate lever 57 at 58. Figure 2. A bracket 60 on the bar 56 carries a stud 61 on which lever 57 is fulcrumed. Lever 57 is 35 flexibly connected to the lower end of the stop setter 53 at 62, see Figures 4 and 5.

35 The key 52 for setting a stop for right-hand margin gaging, is carried on a key lever 63 pivoted on the comb bar 56 and is engageable with an intermediate lever 64 fulcrumed on the stud 61, said lever having a slot 65 riding on said stud. A spring 66 acting on lever 64 yieldably holds 40 said lever in a rightward position with the left end of slot 65 against the stud 61. The free end of lever 64 carries a roller 67 adapted to coact with the cam 46 of the shift lever 44. The slot 65 extends from the stud 61 in a direction substantially at right angles to the general contour of the cam 46.

50 It may be here noted that the arrangement of the stop-setting finger 54 allocates the setting station just to the left of the counterstop in its normal position. To set a stop for left-hand margin gaging, the key 51 is depressed and the intermediate lever 57 pulls the stop setter down and thus sets a stop at the left side of the counterstop, see Figure 4. In setting a stop for right-hand margin gaging, the key 52 is depressed and the intermediate lever 64 is, therefore, actuated. Said lever engages a pin 68 on lever 57 and thus pulls the stop setter down. However, during an initial portion of its stroke, the stop setter merely approaches the stop 34 without engaging same. During this initial movement, the roller 67, cooperating with the cam 46, actuates the shift lever 44 to swing the counterstop to the left of the stop-setting station, see Figure 5, after which the stop is set to effective position to function as a right-hand or line-end stop. The 55 leftward position of the counterstop 36 is defined by the engagement of lug 45 with the left side of slot 48 in the cover plate. Upon release of the stop-setting key 52, the spring 47 urges the counterstop 36 to its normal rightward position, shown in Figure 1, which position the coun-

terstop assumes as soon as the right-hand margin stop is moved away from the stop-setting station.

The slot 65 and spring 66 constitute a yieldable mounting for the lever 64, directed to avoid damage to the setting mechanism when operated to set a right-hand stop with a left-hand stop already in engagement with the counterstop 36, see Figure 13. In setting a right-hand stop, the initial movement of the key 52 brings the roller 67 into coaction with the cam 46 to swing the counterstop 36 leftward. Counterstop movement, however, is obstructed by the left-hand margin stop, with the effect that the shift lever 44 is rendered immovable. Under such conditions, the spring 66 yields to allow the lever 64 to be displaced leftward, as afforded by the slot 65, while the roller 67 rides idly down the cam 46. The lever 64 in swinging about its pivot 61 engages pin 68 and thus operates the stop setter 53 without, however, affecting any stops, in that the setting finger 54 merely idles over the set stop. As soon as key 52 is released, the spring 66 causes the parts to assume their normal, inactive position shown in Figure 1. To assure proper normal operation of the stop-setting mechanism it will be understood that the spring 66 is to be amply strong to withstand the reactionary forces of roller 67 and cam 46 which tend to displace lever 64 endwise from its normal rightward position, Figure 1. Spring 66 is therefore of sufficient strength to overcome the force of spring 47 reacting through the cam and roller 46, 67.

A stop-restoring plunger 70, shown best in Figures 2 and 3, is adapted to engage any one of the stops 34 positioned at the stop station, to restore same to ineffective position on the stop rack. The upper end of the said plunger is slidably retained in the cover plate 50, just forward of the counterstop 36 and has its lower end flexibly connected to an intermediate lever 71, see Figure 1, pivoted at 72. A stop-restoring key 73 is carried on a key lever 74 pivoted at one end on a bracket 75, Figure 2, and includes a prong 76 overlying the free end of lever 71. When the key 73 is depressed, the prong 76 moves downwardly to swing lever 71 and thereby raise the plunger 70 to restore a stop. Upon release of key 73, a spring 77 returns the stop-restoring mechanism to normal, inactive position.

The margin-release mechanism operates to retract the counterstop 36 to ineffective position out of the path of the carriage stops 34, and to releasably latch the counterstop retracted while the carriage is in beyond-the-margin positions, the latching device being automatically released by return of the carriage to within the line-typing zone. A counterstop retractor 80 is mounted for movement up and down, by means hereinafter described, and has a dog 81 projecting laterally therefrom and normally overlying a shoulder 82 on the counterstop 36. An arm 83, forming part of a throw-off device hereinafter described, is swingably mounted at its lower end on the pivot 38 and has a spring 84, anchored to the shift lever 44, yieldably holding said arm in the normal, leftward position shown in Figure 1. As shown more clearly in Figure 14, a pin 85 on said arm is engaged in a slot in the retractor 80. The lower end of the retractor has a slot in which a pin 86 is engaged, said pin being carried on a lever 87 fulcrumed on the stud 61. A spring 88, interposed between the retractor 80 and lever 87, holds the pin 86 normally against

the upper end of the slot. Lever 87 extends rightward beyond its pivot and has a spring 89 acting thereon to yieldably hold the retractor 80 in normal, raised position. A margin-release key 90 is carried on a key lever 91 pivoted on the comb bar 56, said lever being engageable at 92 with the lever 87, Figure 2.

A roller 94, carried on the counterstop 36, cooperates with a latching cam 95 rotatably carried on the shift lever 44. The cam 95 has a series of faces with which the roller 94 may engage, including a central recess 96 and right and left side recesses 97, 98 into each of which the roller 94 may seat when the cam assumes the several angular positions of operation. The upper part of the cam 95 presents a central tooth 100 and right and left teeth 101, 102 angularly spaced in substantial correspondence to the recesses 96, 97, 98. With the roller seated in the central notch 95, the counterstop is projected in the normal carriage-stop-intercepting position; and when seated in either outer recess 97 or 98, the counterstop is retracted out of the carriage stop path. The outer recesses are, therefore, a greater distance from the cam pivot than is the central recess. From this it will be seen that the three recesses, regarded as a composite cam face, present a general contour issuing eccentrically each side of the cam center. The recessed form 30 of the cam contour is employed to also obtain a detenting action of the roller on the cam to detent the latter accurately at its several angular positions, in each of which, one of the teeth 100, 101 or 102 is adapted for engagement by a set 35 carriage stop.

The upper end of arm 83 carries a cam 103 presenting oppositely inclined faces which, in cooperation with a pair of pins 104 on the latching cam 95, functions as a throw-off device to 40 displace the counterstop retractor 83 at a certain phase of operation, and thus throw the retractor dog 81 off the counterstop shoulder 82. This displacement of the actuator 83 by cam 103 also 45 serves to release the line-lock mechanism, hereinafter described.

During the usual line typing between limits defined by the set margin stops 34, the mechanism comprising the counterstop and associated elements for margin release and stop selection 50 maintain substantially the relative positions shown best in Figure 1, except that in banking at a line end, Figure 8, said mechanism is swung leftward en masse. The pivotal axis of the cam 95 on shift lever 44, is substantially in alignment 55 with the upper portion of the counterstop so that the central tooth 100 of said cam is normally aligned with the stop-engageable end of the counterstop when the cam 95 is in its normal, non-released position, defined by the roller 94 seating in the central recess 96. At said position, the two pins 104 engage the opposite inclined faces of cam 103, said cam being pressed 60 against said pins by spring 84. Through the medium of the pin-and-slot connection 85, the spring 84 also holds the retractor 83 in its leftward position defined by the engagement of cam 103 with the pins 104, in which position the dog 81 overlies the counterstop shoulder 82.

The operation of the margin-release mechanism to free the carriage for typing in a left-hand margin, is shown in Figures 6 and 7. When such typing is required, the carriage is usually at the beginning-of-line position, Figure 6, with the carriage stop 34 banked against the counterstop. It may be here noted that, after banking

at the end of a carriage-return run, the carriage drops back a fraction of a letter space to allow the escapement mechanism 22 to again assume control of the carriage, in the well-known manner. The carriage stop 34 has, therefore, receded slightly to the left of the counterstop 36, as shown. To effect margin release into the left margin, the release key 90 is depressed, swinging lever 87 counterclockwise. The pin 86 is thus moved downwardly and, after bottoming in the slot, pulls the retractor 80 down. The dog 81, being engaged with shoulder 82, retracts the counterstop 36 and the roller 94 is thereby withdrawn from the cam recess 96. The mechanism thus assumes the condition shown in dot-and-dash outline in Figure 6, with the counterstop 36 retracted out of the carriage stop path but with the central cam tooth 100 still in the stop path. The carriage is then moved rightwardly, preferably to its limit of movement, and the stop 34 engages tooth 100, rotating cam 95 to a position in which the right-hand recess 97 is substantially aligned with roller 94. While the cam is rotating, the upper pin 104 coacts with cam 103 to shift the retractor 80 rightward, causing the dog 81 to ride off shoulder 82 and release the counterstop. The counterstop is thus freed to move upwardly under influence of spring 43 until arrested by the seating of roller 94 in the cam recess 97, which holds the counterstop retracted, at the same time detenting the cam 95 in the margin-release position, Figure 7. As the dog 81 rides off the counterstop shoulder, spring 88 pulls the retractor farther downwardly to the extent afforded by the pin-and-slot connection 86, so that the dog 81 is well below the level of the shoulder 82, thus preventing a possible re-engagement of these parts at any time, as long as the release key is held down, even though partly released. When the release key is released, the retractor 80 is raised to its normal elevation by spring 89, Figure 1, but is still held rightward free of the counterstop by pin 104 resting on the high part of cam 103, as shown in Figure 7.

When the carriage is brought into the normal line-typing zone, after typing in the left margin, the margin stop 34 is moved leftwardly by this carriage movement and engages tooth 102 of the cam. The resultant rotation of cam 95 causes the roller 94 to ride over the high point between recesses 96 and 97, against the force of spring 43, until said roller seats in the central recess 96, Figure 6, thus allowing the counterstop to rise to effective position in the carriage stop path. In restoring cam 95 to its normal, non-released position, the upper pin 104 rides off the high part of cam 103 and allows the retractor 80 to be moved leftward by spring 84, to thus engage the dog 81 with the counterstop, Figure 1.

When the carriage is banked at line-end position, the counterstop 36 and associated elements are moved leftwardly to the Figure 8 position, at which the machine is locked against typing. In the illustrated embodiment, this line-locking is effected by obstructing movement of the letter-feed universal bar, thereby disabling the letter-feed mechanism; although other well-known modes of line locking may be employed. As shown in Figures 2 and 3, a lock lever 105 is pivoted on bracket 37 to swing horizontally. An arm of said lever extends rearwardly into a slot 106 of the retractor 80. A second arm extends forwardly, having its end 107 normally adjacent an arm 108 of the rockable ball 27. When the retractor 80 is in normal, quiescent position, Figure 1, or in

an operated position to the right thereof, the lever end 107 is clear of arm 108. However, when the retractor 80 is swung leftward from the Figure 1 position, as in line-end gaging, Figure 8, the lever end 107 is moved into abutting relation with arm 108, thereby obstructing movement of the universal bar 26 and preventing the type bars 20 from striking the platen.

The several stages of operation, in effecting margin release from the line-end or right-hand margin position, are shown in Figures 8 to 11. In Figure 8, the banking of the carriage at the line end has shifted the counterstop and associated elements leftward, the counterstop 36 and shift lever 44 swinging about the pivot 38, thus further tensioning spring 47, the force of which holds the counterstop against the carriage stop. As the release key 90 is depressed, the retractor 80 is pulled downwardly, as previously described, drawing the counterstop with it to the position shown in Figure 9, at which the counterstop is about to ride off the carriage stop, and the roller 94 is partly withdrawn from the cam recess 96. When the counterstop does ride off the carriage stop, the parts snap to the position shown in Figure 10, actuated by the spring 47. Accordingly, the counterstop 36 and shift lever 44 have assumed their rightward position against the plate 50, but the cam tooth 100, remaining engaged with the carriage stop, has caused the cam 95 to be rotated initially by the rightward displacement of the cam pivot. This cam rotation has caused the lower pin 104 to coact with cam 103 thereby swinging the retractor 80 rightward to disengage dog 81 from the shoulder 82 to free the counterstop, the roller 94 of which now presses against cam 95. It will be observed that the rightward displacement of the retractor, acting upon the locking lever 105, has released the universal bar 26 and the machine is conditioned for further typing beyond the line end. During this further typing, the carriage stop 34 travels leftward and completes rotation of cam 95, so that the parts assume the Figure 11 position with the roller 94 seated in the cam recess 98, and with the counterstop latched retracted.

To restore the carriage for typing within the normal line-typing zone, the carriage is started in a return run, as shown in Figure 12. The carriage stop 34, proceeding from about the Figure 11 position, comes into engagement with the cam tooth 101, thereby rotating the latching cam 95, which causes roller 94 to ride over the high point between the recesses 96 and 98, the cam rotation continuing until the roller seats in the central recess 96. This cam rotation carries the lower pin 104 off the high part of cam 103 and the retractor 80 is accordingly released to its leftward position under influence of spring 84. Thus, the retractor dog 81 again engages the counterstop shoulder 82 and the parts are restored to the Figure 1 position for normal line typing.

Although in this application, there is specifically described one embodiment which the invention may assume in practice, it will be understood that same is shown for the purposes of illustration, and that the invention may be modified and embodied in various other forms without departing from its spirit or the scope of the appended claims.

I claim:

1. In a typewriter having a reciprocatory carriage; a margin-gaging mechanism including; spaced stops on the carriage defining carriage-stopping points; a counterstop arranged in the

path of carriage-stop travel for engagement by said stops respectively to bar carriage travel, in either direction, at said points; and means for moving, holding and restoring the counterstop in respect to a carriage-stop engagement, said means including devices for withdrawing the counterstop from the path of carriage-stop travel, for holding it so withdrawn as the carriage passes beyond said points and until the carriage is returned to a position in which the counterstop is in advance of stop-engaging position, and for releasing and restoring the counterstop to stop-engaging position when said returned position has been reached.

2. In a typewriter having a carriage movable in letter-space increments, a margin-stop mechanism including a plurality of uniformly-shaped selectively-settable stops arranged, slightly spaced in definite ratio to the letter-space increments, from approximately one end of the carriage to the other, any of the stops, when set for carriage stopping, being in alignment with each other, counterstop means arranged in relation to a set stop to bar carriage travel at a point determined by the particular stop set, means adapted to effect a change in the relationship between the counterstop means and the set stop, irrespective of which of the plurality of settable stops has been set, to permit movement of the carriage beyond said point, and means operable in consequence of return of the carriage from beyond said point, and irrespective of which of the plurality of settable stops has been set, to again set up a relationship between the counterstop means and the set stop to bar carriage travel at said point.

3. In a typewriter having a carriage movable in letter-space increments, a margin-stop mechanism including a plurality of stops arranged, slightly spaced in definite ratio to the letter-space increments, from approximately one end of the carriage to the other and selectively settable in alignment with each other to define the two margins, counterstop means arranged in relation to any two of said stops set on opposite sides thereof to bar travel of the carriage at points determined by the set stops, means adapted to effect a change in the relationship between the counterstop means and one of the set stops to permit movement of the carriage beyond the corresponding one of the points, and means operable in consequence of return of the carriage from beyond said one point to restore the relationship between the counterstop means and said one set stop to bar carriage travel at the said one point.

4. In a typewriter having a carriage movable in letter-space increments, a margin-stop mechanism including a plurality of selectively settable stops arranged respectively at letter-space intervals from approximately one end of the carriage to the other, a single counterstop adapted for arrangement between any two set stops to cooperate with the confronting faces of the two set stops, respectively, in the same upright plane of carriage travel, to determine a normal range of carriage travel which may be varied at will by the setting of different stops, means adapted to effect a change in the relationship between the counterstop and one of the set stops to permit movement of the carriage beyond the normal range of travel, and means operable in consequence of return of the carriage to within the normal range of travel to restore the original relationship between the said one set stop and the counterstop.

5. In a typewriter having a carriage movable in letter-space increments, a margin-stop mechanism including a group of stops near each carriage end, the stops in each group being uniform and arranged at slightly spaced intervals and being selectively settable to identical effective position in alignment with each other, counterstop means arranged in relation to stops set respectively in each of said end groups, and on opposite sides of said counterstop means, to bar travel of the carriage at points determined by the set stops, means adapted to effect a change in the relationship between the counterstop means and either of the set stops to permit movement of the carriage beyond either point, and means operable in consequence of return of the carriage past the point determined by the corresponding stop, to restore the relationship between the counterstop means and the corresponding set stop to bar carriage travel at the said point.
6. In a typewriter having a carriage movable in letter-space increments and a rack on the carriage containing a series of slideable stops arranged at definite intervals from approximately one end of the carriage to the other, key-operable means for selectively setting said stops to present one on each side of a counterstop to define a normal typing range, a counterstop normally held in the path of the set stops on the carriage, key-controlled means for withdrawing the counterstop from said path to allow movement of the carriage in either direction beyond said normal typing range, means to latch said counterstop withdrawn during carriage movement beyond the said range, and means operable upon return of the carriage to within said range, to unlatch the counterstop for resetting it in the path of the set stops on the carriage.
7. A margin-stop-mechanism for a typewriter having a reciprocatory, letter-feed-controlled carriage, comprising in combination, a plurality of identical stops at letter-spaced intervals on the carriage selectively settable in alignment with each other, any two set stops being adapted to define a typing range between normal line ends, a single counterstop normally in the path of the two set stops to gage the normal line ends in travel of the carriage, means to disengage the counterstop and the set stop with which it has engaged, to permit additional carriage travel for typing beyond the line end defined by the engaged stop, and means operable in consequence of restoration of the carriage to within the normal typing range, to restore the said set stop and counterstop to normal relation.
8. A margin-stop mechanism for a typewriter having a reciprocatory carriage, comprising in combination, a plurality of identical stops at letter-spaced intervals on the carriage selectively settable to define a typing range between normal line ends, a single counterstop normally effective to engage a set carriage stop to gage a normal line end, means for rendering said counterstop ineffective to permit additional carriage travel for typing beyond the normal line end, and means for releasably retaining the counterstop ineffective during said additional carriage travel, said retaining means being engageable and actuatable by the set stop and rendered effective or ineffective by relative movement of the set stop and counterstop in appropriate direction.
9. A margin-stop mechanism for a typewriter having a reciprocatory carriage, comprising, in

combination, a stop on the carriage, a counterstop normally urged to effective position to engage the carriage stop for gaging a normal line end of carriage travel, key-operable means for moving the counterstop to clear the carriage stop to permit additional carriage travel for typing beyond the normal line end, and means for releasably holding the counterstop so moved, during said additional carriage travel, said holding means being engageable and actuatable by the carriage stop, rendered effective by carriage-stop movement in one direction and rendered ineffective by carriage-stop movement in the opposite direction.

10. A margin-stop mechanism for a typewriter having a reciprocatory carriage, comprising, in combination, a stop on the carriage, a retractable counterstop normally urged to effective position to engage the carriage stop for gaging a normal line end of carriage travel, means for retracting the counterstop to clear the carriage stop to permit additional carriage travel in one direction for typing beyond the normal line end, and a latching device engageable and rendered effective by the carriage stop during said additional carriage travel, to latch the counterstop retracted, and engageable and rendered ineffective by the carriage stop in carriage travel in the opposite direction, to automatically release the counterstop for return to effective position.

11. A margin-stop mechanism for a typewriter having a reciprocatory carriage, comprising, in combination, a stop on the carriage, a retractable counterstop normally urged to effective position to engage the carriage stop for gaging a normal line end of carriage travel, means for retracting the counterstop to clear the carriage stop to permit additional carriage travel in one direction for typing beyond the normal line end, and a pivoted latching member swingable in opposite directions in a plane of carriage travel upon engagement of the carriage stop therewith, to latch the counterstop retracted during said additional carriage travel and, during carriage travel in the opposite direction, to release the counterstop for return to effective position.

12. A margin-stop mechanism for a typewriter having a reciprocatory, letter-feed-controlled carriage, comprising in combination, margin-gaging stops on the carriage defining a typing range between normal line ends, a retractable counterstop normally urged to stop-intercepting position for gaging the normal line ends, key-operable means to retract the counterstop to permit additional carriage travel for typing beyond a normal line end, a rotatable cam actuatable by the carriage stops and operative, upon relative stop and counterstop movement in one direction, to hold the counterstop retracted, said cam being actuatable to free the counterstop for restoration to stop-intercepting position, upon relative movement of the stops and counterstop in an opposite direction.

13. A margin-stop mechanism for a typewriter having a reciprocatory carriage, comprising, in combination, a stop on the carriage, a retractable counterstop normally urged to effective position to intercept the carriage stop for gaging a normal line end of carriage travel, means for retracting the counterstop to clear the carriage stop to permit additional carriage travel for typing beyond the normal line end, a cam follower on said counterstop, a rotatable cam having a series of faces on which said follower is seatable, the faces

being differently spaced from the cam axis to gage the counterstop at stop-clearing and stop-intercepting positions, said cam having portions engageable by the carriage stop in reciprocatory carriage travel, to rotate the cam to the different counterstop-gaging positions.

14. A margin-stop mechanism for a typewriter having a reciprocatory carriage, comprising in combination, margin stops on the carriage defining a typing range between normal line ends, a retractable counterstop normally urged to stop-intercepting position, normally effective key-operable means for retracting the counterstop for typing beyond the normal line ends, releasable latching means engageable by the carriage stops and operative upon relative stop and counterstop movement in one direction after stop interception, to latch the counterstop retracted during typing beyond the normal line ends, and to unlatch the counterstop in relative stop and counterstop movement in an opposite direction, and means actuatable by said latching means and rendered effective upon said relative stop and counterstop movement in the one direction, to disable said retracting means, said disabling means, upon relative stop and counterstop movement in an opposite direction, being rendered ineffective, to recondition said retracting means for counterstop retraction.

15. A margin-stop mechanism for a typewriter having a reciprocatory carriage, comprising in combination, margin stops on the carriage defining a typing range between normal line ends, a retractable counterstop normally urged to stop-intercepting position, normally effective key-operable means for retracting the counterstop to permit typing beyond the normal line ends, releasable latching means engageable by the carriage stops and operative upon relative stop and counterstop movement in one direction after stop interception, to latch the counterstop retracted, and means operable by said latching means in latching the counterstop, to disable said retracting means, said latching means, upon relative stop and counterstop movement in an opposite direction, being releasable to free the counterstop for restoration and render said disabling means ineffective.

16. A margin-stop mechanism for a typewriter having a reciprocatory, letter-feed-controlled carriage, comprising in combination, margin-gaging stops on the carriage defining a typing range between normal line ends, a retractable counterstop normally urged to stop-intercepting position for gaging the normal line ends, a key-operable retractor adapted for coupling with the counterstop, normally urged to coupled relation therewith and operative to retract the counterstop to permit additional carriage travel for typing beyond a normal line end, releasable latching means engageable by the carriage stops and operative upon relative stop and counterstop movement in one direction, for latching the counterstop retracted, and means operable by said latching means to uncouple said retractor from the counterstop and thereby release the counterstop to control of the latching means, said latching means being releasable to free the counterstop for restoration to stop-intercepting position, upon relative stop and counterstop movement in an opposite direction in restoring the carriage to within the normal typing range.

17. A margin-stop mechanism for a typewriter having a reciprocatory, letter-feed-controlled carriage, comprising in combination, margin-

gaging stops on the carriage defining a typing range between normal line ends, a retractable counterstop normally urged to stop-intercepting position for gaging the normal line ends, a key-operable retractor adapted for coupling with the counterstop, normally urged to coupled relation therewith and operative to retract the counterstop to permit additional carriage travel for typing beyond a line end, a rotatable cam actuatable by the carriage stops and operative upon relative stop and counterstop movement in one direction, to hold the counterstop retracted, and means operable by said cam to uncouple said retractor from the counterstop and thereby release the counterstop to control of the cam, said cam being actuatable to free the counterstop for restoration to stop-intercepting position, upon relative movement of the stops and counterstop in an opposite direction in restoring the carriage to within the normal typing range.

18. A margin-stop mechanism for a typewriter having a reciprocatory carriage, comprising, in combination, a plurality of identical stops at letter-spaced intervals on the carriage, selectively key-settable at a station to define a normal typing range between normal line ends, a retractable counterstop normally urged to carriage-stop-intercepting position to gage a normal line end, means mounting said counterstop for shifting in the direction of carriage travel, between limits defining a normal position to the right of said stop-setting station and a shifted position to the left of said station, means yieldably holding the counterstop in the normal rightward position, means to retract the counterstop to stop-clearing position to permit additional carriage travel for typing beyond the normal line end, and means engageable and actuatable by a set carriage stop to latch the counterstop retracted during said additional travel, and engageable and releasable by a set stop in carriage travel to within the normal typing range, to automatically release the counterstop to effective position.

19. A margin-stop mechanism for a typewriter having a reciprocatory, letter-feed controlled carriage, comprising in combination, a plurality of identical stops at letter-spaced intervals on the carriage, selectively key-settable at a station to define a normal typing range between normal line ends, a retractable counterstop normally urged to carriage stop-intercepting position to gage a normal line end, means mounting said counterstop for shifting in the direction of carriage travel, between limits defining a normal position to the right of said stop-setting station and a shifted position to the left of said station, means yieldably holding the counterstop in the normal rightward position, means to retract the counterstop to stop-clearing position to permit additional carriage travel for typing beyond the normal line end, and a latching device carried on said mounting means and engageable and actuatable by a set carriage stop to latch the counterstop retracted during said additional travel, and engageable and releasable by a set stop in carriage travel to within the normal typing range, to automatically release the counterstop to effective position.

20. A margin-stop mechanism for a typewriter having a reciprocatory, letter-feed controlled carriage, comprising in combination, a plurality of identical stops at letter-spaced intervals on the carriage, key-settable at a station to define a typing range between normal line ends, a retractable

counterstop normally urged to carriage stop-intercepting position to gage a normal line end, means including a shift member mounting said counterstop for shifting in the direction of carriage travel, between limits defining a normal position to the right of said stop-setting station and a shifted position to the left of said station, means yieldably holding the counterstop in the normal rightward position, means to retract the counterstop to stop-clearing position to permit additional carriage travel for typing beyond the normal line end, and a latching device carried on said shift member and engageable and actuatable by a set carriage stop to latch the counterstop retracted during said additional travel, and engageable and releasable by a set stop in carriage travel to within the normal typing range, to automatically release the counterstop to effective position.

21. A margin-stop mechanism for a typewriter having a reciprocatory, letter-feed controlled carriage, comprising in combination, a plurality of identical, settable stops at letter-spaced intervals on the carriage, key-operable means to set any one of said stops, positioned by carriage movement, at a stop-setting station, a retractable counterstop normally urged to carriage stop-intercepting position to gage a normal line end, means including a shift lever mounting said counterstop for shifting in the direction of carriage travel, between limits defining a normal position to the right of said stop-setting station and a shifted position to the left of said station, means yieldably holding the counterstop in the normal shift position, means to retract the counterstop to stop-clearing position to permit additional carriage travel for typing beyond the normal line end, and means carried on said shift lever to releasably hold the counterstop retracted and actuatable by a set stop, to be rendered effective or ineffective thereby, depending on the direction of stop movement, said key-operable means including a pair of keys and means operable by one of said keys to actuate said shift lever to move the counterstop leftward prior to stop setting.

22. A margin-stop mechanism for a typewriter having a reciprocatory, letter-feed-controlled carriage, comprising, in combination, a plurality of identical, settable stops at letter-spaced intervals on the carriage, key-operable means to set any one of said stops, positioned by carriage movement, at a stop-setting station, a single counterstop normally effective to engage a set carriage stop to gage a normal line end, means including a shift lever mounting said counterstop for shifting in the direction of carriage travel, between limits defining a normal position to the right of said stop-setting station and a shifted position to the left of said station, and means yieldably holding the counterstop in the normal rightward position, said key-operable means including a pair of keys, associated actuating levers and a cam-and-follower device operable by the lever of one of said keys to actuate said shift lever and thereby shift the counterstop leftward prior to stop setting, said cam-and-follower operating lever having a yieldable device associated therewith allowing said cam-and-follower to idle although said shift lever is blocked against movement.

23. A margin-stop mechanism for a typewriter having a reciprocatory, letter-feed-controlled carriage, comprising in combination, a plurality of letter-spaced stops on the carriage, means to

set any of said stops, positioned by carriage movement, at a stop-setting station, for gaging the normal right and left line-ends, a retractable counterstop normally urged to position to intercept the set stops, means including a shift member mounting said counterstop for limited shifting in the direction of carriage travel to opposite sides of said setting station, means yieldably holding the counterstop at one side of said station, a key-operable retractor adapted for coupling with the counterstop and normally urged to coupled relation therewith and operative to retract the counterstop to permit additional carriage travel for typing beyond a normal line end, counterstop latching means carried on said shift member, engageable by the set stops and operative to latch the counterstop retracted, after stop interception and upon relative movement of the stop and the counterstop with the shift member, following counterstop retraction, means operable by said latching means to uncouple the retractor from the counterstop and thereby release the counterstop to control of said latching means, said latching means being releasable to free the counterstop for restoration to stop-intercepting position, upon movement of the stops in a direction opposite that by which the latching means is first rendered operative.

24. A margin-stop mechanism for a typewriter having a reciprocatory letter-feed-controlled carriage, comprising in combination, a plurality of letter-spaced stops on the carriage, means to set any of said stops, positioned by carriage movement, at a stop-setting station, for gaging the normal right and left line-ends, a retractable counterstop normally urged to position to intercept the set stops, means including a shift member mounting said counterstop for limited shifting in the direction of carriage travel to opposite sides of said setting station, means yieldably holding the counterstop at one side of said station, a key-operable retractor adapted for coupling with the counterstop and normally urged to coupled relation therewith and operative to retract the counterstop to permit additional carriage travel for typing beyond a normal line end, a rotatable cam carried on said shift member, engageable by the set stops and operative to hold the counterstop retracted, after stop interception and upon relative movement of the stop and the counterstop with the shift member, following counterstop retraction, means operable by said cam to uncouple the retractor from the counterstop and thereby release the counterstop to control of said cam, said cam being operable to free the counterstop for restoration to stop-intercepting position, upon movement of the stops in a direction opposite that by which the latching means is first rendered operative.

25. A margin-stop mechanism for a typewriter having a reciprocatory, letter-feed-controlled carriage, comprising in combination, a plurality of letter-spaced stops on the carriage, key-operable means to selectively set any of said stops, positioned by carriage movement, at a stop-setting station, for gaging the normal right and left line-ends, a retractable counterstop normally urged to position to intercept the set stops, means including a shift member mounting said counterstop for shifting between limits defining a normal position to the right of said stop-setting station and a shifted position to the left of said station, means yieldably holding the counterstop in said normal, rightward position, said key-operable stop-setting means being selec-

tively operable, means operable by said setting means when operated selectively, to shift said member leftward prior to setting a stop for gaging a right line end, a key-operable retractor adapted for coupling with the counterstop, normally urged to coupled relation therewith and operative to retract the counterstop to permit additional carriage travel for typing beyond a normal line end, counterstop latching means carried on said shift member, engageable by the set carriage stops and rendered effective to hold the counterstop retracted, after stop interception and upon stop movement rightward or counterstop and member movement rightward, following counterstop retraction, and means operable by said latching means to uncouple the retractor from the counterstop and thereby release the counterstop to control of said latching means, said latching means being releasable to free the counterstop for restoration to stop-intercepting position, upon movement of the stops in a direction opposite that by which the latching means is rendered effective.

26. In a typewriting machine having typing instrumentalities, a letter-feed-controlled, reciprocatory carriage and a line-lock device for disabling the typing instrumentalities; a margin-stop mechanism comprising, in combination, a series of letter-spaced stops on the carriage, settable at a stop-setting station, for gaging the normal line ends, a retractable counterstop normally urged to stop-intercepting position, means including a shift member, mounting said counterstop for shifting between limits defining a normal position to the right of said stop-setting station and a shifted position to the left of said station, means yieldably holding the counterstop in the normal rightward position, a key-operable retractor operatively connected to the line-lock device and adapted for coupling with the counterstop, being normally urged to coupled relation therewith, the line-lock device being ineffective with said retractor coupled and the counterstop in normal rightward position, leftward travel and interception of a set stop by the counterstop causing shifting of the counterstop and retractor to operate the line-lock device, releasable latching means carried on said shift member and actuatable by the set carriage stops to latch the counterstop retracted after operation of the retractor, and means operable by said latching means to uncouple the retractor and thereby release the line-lock device and free the counterstop to control of the latching means, said latching means being releasable to free the counterstop for restoration to stop-intercepting position and to allow recoupling of the retractor, upon movement of the effective, set stop in a rightward direction of carriage travel.

27. A margin-stop mechanism for a typewriter having a reciprocatory carriage, comprising, in combination, a plurality of letter-spaced stops on the carriage, key-operable means to set any of said stops, positioned by carriage movement, at a stop-setting station, for gaging the normal right and left line ends, a retractable counterstop normally urged to position to intercept the set stops, means including a shift member mounting said counterstop for shifting between limits defining a normal position to the right of said stop-setting station and a shifted position to the left of said station, means yieldably holding the counterstop in said normal, rightward position, said key-operable setting means including a pair of keys and means operable by one of said keys

to shift said member leftward prior to setting a stop for gaging the right line end, a key-operable retractor adapted for coupling with the counterstop, normally urged to coupled relation therewith and operative to retract the counterstop to permit additional carriage travel for typing beyond a normal line end, latching means carried on said shift member, engageable by the set stops and rendered effective to hold the counterstop retracted, after stop interception and upon stop movement rightward or counterstop and shift member movement rightward, following counterstop retraction, and means operable by said latching means to uncouple the retractor from the counterstop and thereby release the counterstop to control of said latching means, said latching means being releasable to free the counterstop for restoration to stop-intercepting position, upon movement of the stops in a direction opposite that by which the latching means was rendered effective.

28. A margin-stop mechanism for a typewriter having a reciprocatory, letter-feed-controlled carriage, comprising in combination, a plurality of letter-spaced stops on the carriage, means to set any of said stops, positioned by carriage movement, at a stop-setting station, for gaging the normal line ends, a counterstop normally urged to stop-intercepting position, means mounting said counterstop for endwise retractive movement transversely of the direction of carriage travel and for pivotal movement in the direction of carriage travel, a pivoted shift member slidably guiding said counterstop, means including said shift member for limiting counterstop pivotal movement between a normal position to the right of said stop-setting station and a shifted position to the left of said station, means acting on said shift member for yieldably holding the counterstop in the normal rightward position, a key-operable retractor mounted for oscillatory movement to and from the counterstop and endwise movement with the counterstop, said retractor having a part engageable with the counterstop to retract the latter to stop-clearing position for typing beyond a normal line end, means urging said retractor to counterstop engagement, a rotatable cam on said shift member, engageable and actuatable by the set carriage stops and adapted, in moved position, to hold the counterstop retracted, and a cam fixed on said retractor, said rotatable cam having a projection cooperative with said fixed cam to swing the retractor out of counterstop engagement, a rotatable cam on said shift member, engageable and actuatable by the set carriage stops and adapted, in moved position, to hold the counterstop retracted, and a cam fixed on said retractor, said rotatable cam having a projection cooperative with said fixed cam to swing the retractor out of counterstop engagement.

ment when the rotatable cam is actuated to moved position, to thereby release the counterstop to control of the rotatable cam, said rotatable cam, upon return of the carriage from beyond a normal line end, being returned from moved position by the associated carriage stop to release the counterstop to effective position and to release the retractor for counterstop reengagement.

29. A margin-stop mechanism for a typewriter having a reciprocatory, letter-feed-controlled carriage, comprising, in combination, a plurality of letter-spaced stops on the carriage, key-operable means to set any of said stops, positioned by carriage movement, at a stop-setting station, for gaging the normal line ends, a counterstop normally urged to stop-intercepting position, means mounting said counterstop for endwise retractive movement transversely of the direction of carriage travel and for pivotal movement in the direction of carriage travel, a pivoted shift member slidably guiding said counterstop, means including said shift member for limiting counterstop pivotal movement between a normal position to the right of said stop-setting station and a shifted position to the left of said station, means acting on said shift member for yieldably holding the counterstop in the normal rightward position, a key-operable retractor mounted for oscillatory movement to and from the counterstop and endwise movement with the counterstop, said retractor having a part engageable with the counterstop to retract the latter to stop-clearing position, means urging said retractor to counterstop engagement, a rotatable cam on said shift member, engageable and actuatable by the set carriage stops and adapted, in moved position, to hold the counterstop retracted, a cam fixed on said retractor, said rotatable cam having a projection cooperative with said fixed cam to swing the retractor out of counterstop engagement when the rotatable cam is actuated to moved position, to thereby release the counterstop to control of the rotatable cam, said rotatable cam, upon return of the carriage from beyond a normal line end, returned from moved position by the associated carriage stop to release the counterstop to effective position and to release the retractor for counterstop reengagement, said stop-setting means including means operable on said shift member to shift the counterstop to its leftward position prior to setting of a stop at the right of the counterstop.

WILLIAM F. HELMOND.
